FIG. 1 is a perspective view of a battery-powered shaver showing my new design, with cover in place;

FIG. 2 is a perspective view with the cover in exploded relationship with the shaver;

FIG. 3 is a front elevational view with the cover omitted;

FIG. 4 is a rear elevational view with the cover omitted;

FIG. 5 is a right side elevational view with the cover omitted;

FIG. 6 is a left side elevational view with the cover omitted;

FIG. 7 is a bottom plan view; and

FIG. 8 is a top plan view with the cover omitted.

A characteristic feature in side and end elevation views is a generally rectangular appearance of the lower section; this section is substantially larger than the upper section which is tapered in said views.

I claim:

The ornamental design for a battery-powered shaver, as shown.
